COOLANT SYSTEM

James J. Prendergast, Erie, Pa., assignor to General Electric Company, a corporation of New York

Application December 27, 1952, Serial No. 328,197

10 Claims. (Cl. 123—41.12)

This invention relates to coolant systems, and more particularly to coolant systems for machinery and lubricating oil coolers on locomotives.

An object of the invention is to provide a coolant system, requiring only a single circulating pump, for simultaneously cooling lubricating oil and various items of machinery, under varying conditions of operation.

A further object of my invention is to provide a system of the character described in the preceding paragraph in which a single radiator or set of radiators may be employed for cooling the coolant for all of the items mentioned.

Another object of my invention is to provide a coolant system for an internal combustion engine which keeps the engine warm during stand-by periods and provides for rapid warm-up to full operating temperature when operation of the engine is begun.

Other objects, features and advantages of my invention are pointed out, in part, and will be apparent in part from the subsequent description of a preferred embodiment of the invention, while the scope of the invention is defined in the appended claims.

In carrying out my invention in one form, I provide a coolant system for the lubricating oil, an auxiliary diesel engine and an air compressor on a locomotive. A single pump withdraws coolant from a storage tank and circulates it through an oil cooler and through the engine and compressor. A portion of the coolant discharged from the pump is circulated through the oil cooler and then through a radiator, after which at least a part of this portion circulates through the engine under stand-by conditions when the engine is not operating. The radiator is provided with a fan which operates whenever conditions in the system require it. When the engine is started, the circulation of coolant from the pump is interrupted for a sufficient time to allow the engine to reach full operating temperature, after which circulation of coolant from the pump is resumed to aid in keeping the engine cool during operation.

For a clearer and more complete understanding of my invention reference should be had to the accompanying drawing, the single figure of which is a schematic diagram of the coolant system of my invention as used on a gas turbine-electric locomotive.

Referring to the drawing, there is shown a coolant system for a gas turbine-electric locomotive which is equipped with a lubricating oil heat exchanger 10, an auxiliary diesel engine 11 and an air compressor 12. The coolant system includes a coolant storage tank 13, a centrifugal pump 14 for withdrawing coolant from tank 13 and circulating it through the remainder of the system, and a pair of radiators 15 and 16.

It is desirable that the water or the coolant in tank 13 be kept warm, and I disclose in my copending application Serial No. 328,196, for a Piping System, filed concurrently herewith, and assigned to the assignee of the present application, an arrangement by which condensate from a steam system is discharged into the coolant tank as through a pipe or conduit 17 to keep the water in the

2

coolant tank warm. My copending application also shows an arrangement, not shown in the present application, for admitting a small amount of heated water from a steam generator on the locomotive to the coolant tank to aid in keeping the coolant warm. With either or both of these arrangements, it is desirable to have an overflow pipe 18 extending upwardly into the coolant storage tank to provide a predetermined level in the coolant tank by discharging any excess of coolant through the said pipe; 5 in the aforementioned copending application, such overflow is returned to the main water storage tank. It will be readily understood, of course, that other means may be provided for maintaining the level in the coolant tank and for heating this coolant without departing from the present invention.

In the system illustrated, coolant is withdrawn from tank 13 by pump 14 and discharged under pressure into a pipe or conduit 19. From conduit 19, a portion of the coolant passes through a smaller pipe 20, thence through the cooling water jacket of a compressor 12 and is returned through a return pipe 21 back to the coolant storage tank 13.

The remainder of the coolant discharged by pump 14 passes through lubricating oil heat exchanger 10 in heat exchange relation with the lubricating oil passing therethrough. Heat exchanger 10 may be of any conventional type, and as shown the lubricating oil enters the heat exchanger through a pipe or conduit 21a and is discharged through a pipe 22. In a typical case, the lubricating oil 25 passing through heat exchanger 10 was used to supply lubrication and cooling for the main gas turbine and gears (not shown) on a gas turbine-electric locomotive, although the invention is not limited to such use.

The coolant discharged from heat exchanger 10 passes 30 through a conduit 23 and then through radiators 15 and 16 in series, these two radiators being interconnected by a pipe or conduit 24.

After leaving radiator 16 the coolant passes downwardly 35 through a conduit 25, from which a portion of the coolant 40 passes through a conduit 26. The latter conduit is smaller in size than conduit 25 so that only a portion of the coolant from conduit 25 is able to pass through conduit 26. The coolant from conduit 26 passes into a discharge conduit or pipe 27 by means of which it is returned to 45 the coolant tank 13. It will be understood, of course, that conduit 26 may be provided with an orifice if desired in order to restrict the flow therethrough instead of making it of smaller diameter than pipe 25.

The portion of coolant from pipe 25 which is unable 50 to pass through pipe 26 flows through a conduit 28 and into a second lubricating oil heat exchanger or cooler 29 which is for the engine 11 only. This lubricating oil cooler like cooler 10 may be of conventional construction, and as shown, the lubricating oil is discharged from 55 the cooler through a pipe 30 and returned to the engine, the oil inlet to this cooler not being shown in order to simplify the drawing.

As shown in the drawing schematically by means of dashed lines, the coolant from conduit 28 passes through 60 cooler 29 into a pipe or conduit 31 from which it enters the cooling water jacket of engine 11. After passing through the engine coolant jacket, and an internal pump 37 the coolant is discharged from the engine through an outlet chamber 36 and then through one or two parallel 65 outlet conduits, depending upon operating conditions. When the engine is not running, the coolant is discharged from chamber 36 through a pipe 32 and a normally open valve 33 into a conduit 34 which returns it to discharge conduit 27 and thence back to the coolant tank. When engine 11 is operating, the normally open valve 33 is closed, and then, providing the engine is up to full operating 70 temperature, coolant is discharged through a pipe 35 into

pipe 34. The coolant outlet chamber 36 on engine 11 includes two valves responsive to the temperature of the coolant. One of these, valve 38, is normally closed but opens upon the occurrence of a predetermined temperature of the coolant in outlet chamber 36 to admit coolant to pipe 35. The other valve which is designated 39 is also normally open but closes upon the occurrence of a second predetermined coolant temperature slightly higher than the temperature which causes valve 38 to operate. A suitable arrangement for valves 38 and 39 and chamber 36 is shown schematically in the drawing, but it will be understood that other equivalent arrangements may be employed.

If engine 11 serves as a stand-by unit to provide a source of auxiliary power when needed, and is to be ready for instant operation, it is desirable to keep it warm. This will be accomplished by the present system providing the coolant flowing through pipe 25 is of the proper temperature to impart heat to the engine as a portion of this coolant flows therethrough, and as set forth in detail subsequently this is the case in the present system.

However, even though engine 11 is kept warm in this manner, it is not kept up to operating temperature. Therefore, when the engine starts it is desired to have it reach operating temperature as quickly as possible. This is accomplished by the electrical control and coolant bypass arrangement illustrated on the accompanying drawing and described in the succeeding paragraph.

A conduit 40 having a check valve 41 therein connects the conduit 32 and the junction of conduits 28 and 31 within oil cooler 29. The check valve 41 is arranged so that coolant can flow only from the outlet chamber 36 of the engine back to the coolant inlet conduit 31. The engine 11 is provided with an electrical control system energized from a suitable source of electric current indicated by lines 42 and 43. When a switch 44 is closed, an electrically operated valve 45 is actuated to admit fuel to the engine, and simultaneously the coil of a solenoid 46 is energized to close the normally open valve 33. Then when the engine starts, the internal coolant pump 37 in the engine circulates coolant out through the outlet chamber 36, through conduit 40 and check valve 41, and thence through lubricating oil cooler 29 and conduit 31 back into the engine coolant jacket again. This flow continues until the engine has reached a temperature sufficient to open the valve 38 in the outlet chamber 36 and permit coolant to be discharged through pipe 35 and back to the coolant tank 13 again. Then, a portion of the coolant circulates through the by-pass 40 while the balance of the coolant required for engine 11 is admitted from conduit 28 and after passing through the engine is discharged through conduit 35 and back to the coolant tank, the latter portion recirculating continuously through the lubricating oil heat exchanger 10 and through the radiators 15 and 16. Ultimately, when the coolant in chamber 36 reaches the second predetermined temperature mentioned previously, valve 39 closes to stop circulation of coolant through the by-pass. In this manner, the engine 11 is brought up to operating temperature quickly, and thereafter is maintained at operating temperature.

It will be readily understood that in the interval for starting and warming up engine 11 during which both the normally open valve 33 and valve 38 in the engine coolant outlet lines are closed, that there is a reduced flow of coolant through oil cooler 10 and radiators 15 and 16, due to the fact that all the coolant passing through these devices must pass also through conduit 26. However, this reduced flow is maintained for only a short time, which does not seriously affect the operation of the system, and normal flow is resumed as soon as valve 38 opens. Also, it may be pointed out that the temporary reduction in flow is not directly proportional to the amount of restriction imposed in the conduit system, but is less than this, because of an increase in pump pressure when the volume of flow tends to drop off.

A pipe 47 may be included for conducting any air or other vapor which accumulates in the top of the casing of pump 14 up to the top of tank 13 above the liquid in the tank, from which it may pass out to the atmosphere through pipe 17. Radiators 15 and 16 likewise may be provided with small air vent pipes 48 and 49.

If the various items of equipment are arranged on the locomotive or other rail vehicle or machine in approximately the relative position shown schematically on the accompanying drawing, i. e., with all of the other items of equipment higher than the coolant tank, and if a small pipe 50 is provided connecting the conduit 24 with the tank, and a small pipe 50a is provided connecting the lowest point of the engine coolant jacket with the tank, as shown, the entire system will be self draining.

When pump 14 is stopped, and the engine 11 is not operating, all of the coolant in the system will drain back to the coolant tank. This is very desirable on a locomotive, for example as it minimizes the possibility of coolant in the radiators and other portions of the system freezing during inoperative periods in cold weather. It will be recognized, of course, that pipes 50 and 50a should be sufficiently small in size that they do not affect the normal operation of the system appreciably.

The arrangement for maintaining the coolant at the proper temperature in the various parts of the coolant system includes a pair of fans 51 and 51a for blowing air respectively through radiators 15 and 16, motors 52 and 53 connected to and driving these fans, three temperature responsive electric switches as described in detail below, and suitable electrical connections to incoming mains 42 and 43.

A first electric switch 54 is operated responsively to the temperature of lubricating oil in conduit 22. As illustrated schematically, switch 54 includes a snap acting movable member 55 which normally is in engagement with a fixed contact 56, but upon the occurrence of a predetermined oil temperature in conduit 22 member 55 moves upwardly to engage contact 57. As shown by way of illustration, the operating mechanism for switch 54 comprises a bulb 60 located in conduit 22, the bulb 60 containing a fluid which increases in volume with the temperature. The bulb 60 is connected by means of a conduit 59 to a bellows 58 which operates member 55 between its two positions with a snap action, such snap action being produced by a suitable mechanism which is indicated schematically at 66.

A second switch 61 having a normally open fixed contact 62, a movable member 63, and a normally closed fixed contact 64 is similarly arranged to be operated responsively to the temperature of the oil in conduit 22, the operating means for switch 61 comprising a bulb 69 located in conduit 22 and containing a temperature responsive fluid, a tube 68 connecting bulb 69 with a bellows 67, and a snap acting mechanism for the switch illustrated schematically at 65. Preferably switches 54 and 61 are set to operate at different temperatures. For example, switch 54 may be set to operate at 125° F., while switch 61 is set to operate at 130° F. This means that only one of the two radiator fans operates in many cases when one fan is sufficient to maintain the lubricating oil at a suitable temperature. The exact manner in which this operation is achieved is discussed in detail hereinafter.

A third switch 73 having a bridging member 74 and normally open contacts 75 is operated responsively to the temperature of coolant in tank 13. As shown schematically the operating mechanism for switch 73 includes a bulb 70 located in the tank and containing a temperature responsive fluid, the bulb 70 being connected by a tube 71 to a bellows 72 which operates the bridging member 74 upon an increase in the temperature of the coolant in tank 13 above a predetermined value to close the switch.

As shown motors 52 and 53 both are connected to one

electrical supply conductor 42 by means of a conductor 76. The other terminal of motor 52 is connected by a conductor 77 to the movable member 55 of switch 54. The other terminal of motor 53 is connected by a conductor 78 to the movable member 63 of switch 61. The fixed terminal 62 of switch 61 is connected to the other electrical supply conductor 43 by means of conductors 79 and 80. An additional conductor 81 connects the fixed terminal 57 of switch 54 to terminal 62 and thereby to the supply conductor 43.

Assume now for purposes of explanation of the operation of this system that the locomotive on which it is installed is operating normally, i. e. the main gas turbine and other machinery on the locomotive are operating so that considerable heat is being imparted to the lubricating oil being circulated through heat exchanger 10, but engine 11 is not running so that it is imparting no heat to the coolant circulating therethrough. Under these conditions, if the temperature of the oil leaving the heat exchanger 10 through pipe 22 should reach 125° F., switch 54 will operate to complete the circuit for the operation of fan 51. This circuit may be traced from conductor 42 to conductor 43 through the following circuit: conductor 76, motor 52, conductor 77, switch 54 (movable member 55 being in engagement with contact 57 at this time), conductor 81, conductor 79 and conductor 80. Fan 51 will then cool the coolant being circulated through the lubricating oil heat exchanger 10, and if this provides sufficient cooling, the system will continue in operation in this manner. If, however, the single fan 51 does not provide sufficient cooling so that the temperature of the oil in pipe 22 continues to rise, switch 61 will be operated when the temperature of this oil reaches 130° to initiate the operation of fan 51a. The circuit for this fan may be traced in a similar manner to the other as follows: From main conductor 42 through conductor 76, motor 53, conductor 78, movable member 63 of switch 61, contact 62 of switch 61, conductor 79, and conductor 80 back to the other main conductor 43. Any time that the temperature of the lubricating oil in the conduit 22 drops again for any reason, the fans will be stopped in reverse order to that in which they were started. In this manner the lubricating oil on the locomotive is maintained automatically at a suitable operating temperature.

Next assume that the main gas turbine is not operating, but that auxiliary engine 11 is operating. Under these conditions considerable heat will be imparted to the coolant by engine 11, but a relatively small amount by the lubricating oil in heat exchanger 10. Under these circumstances, if the coolant in tank 13 increases in temperature to a predetermined value such as 135° F., for example, due to the warm coolant being discharged into the tank from engine 11, switch 73 will be operated. The closing of this switch starts the operation of both fans to cool the coolant circulating through the radiators and thence through the engine 11. The two fan motors will be energized through a circuit which may be traced as follows: For motor 52, from conductor 42 through conductor 76, through motor 52, conductor 77, switch 54 which now is in its lower position shown in the drawing in which member 55 engages contact 56, a conductor 82 connecting contact 56 to the left contact 75 of switch 74, through switch 74, and through conductor 80 back to conductor 43. The circuit for motor 53 may be traced from conductor 76 through motor 53, conductor 78, switch 61 in its lower position, conductor 82, switch 74 and through conductor 80 back to main conductor 43.

It is not essential to my invention to have two radiators and a separate fan for each, and a single radiator and fan can be used if desired without departing from the invention, however, I have found that the arrangement described above provides a very good regulation of the coolant temperature under variable operating conditions. Also, while I have shown direct current motors driving the

fans and connected directly in the electrical control system, it will be readily understood that other arrangements may be used, such, for example, as alternating current motors having their starting switches operated by the direct current control system.

It will be apparent from the foregoing that my invention provides a coolant system which maintains the lubricating oil and a stand by internal combustion engine warm and ready for immediate operation, and at the same time provides for automatically cooling both the oil and the engine during operation. These things are accomplished with a system which embodies a single external circulating pump and a relatively small amount of piping and electrical equipment.

While I have illustrated and described a preferred embodiment of my invention, it will be understood that modifications thereof may be made by those skilled in the art. Accordingly, it should be understood that I intend to cover by the appended claims all such modifications which fall within the true spirit and scope of the invention.

What I claim as new and desire to secure by Letters Patent of the United States is:

1. A coolant system for an oil cooler and an engine comprising, a tank for containing a supply of coolant, a pump for withdrawing coolant from the said tank and circulating it through the oil cooler and the engine, conduit means connecting said tank, said pump, the cooler and the engine so that coolant discharged by the pump flows through the oil cooler and that at least a portion of said coolant from the cooler flows through the engine with substantially all of the coolant discharged by said pump being returned to said tank for recirculation through the system, a radiator connected in circuit with said conduit means between said pump and the engine whereby at least a portion of the coolant discharged by said pump flows through said radiator, a fan for circulating air through the said radiator to cool the coolant passing therethrough, means responsive to the temperature of oil leaving the cooler for starting the operation of said fan, and means responsive to the temperature of the coolant in said tank for starting the operation of the said fan.

2. A coolant system for a fluid heat exchanger and an engine comprising, a tank for containing a supply of coolant, a pump for withdrawing coolant from said tank and circulating it through the exchanger and the engine, a radiator for cooling said coolant, conduit means connecting said tank, said pump, said radiator, the exchanger and the engine so that coolant discharged by said pump flows through the heat exchanger and said radiator and that at least a portion of the coolant passing through said radiator flows also through said engine, substantially all of the coolant discharged by said pump being returned to said tank for recirculation, a fan for circulating air through said radiator to cool the coolant flowing therethrough, means responsive to the temperature of fluid leaving the fluid heat exchanger for starting the operation of said fan, and means responsive to the temperature of the coolant in said tank for starting the operation of the said fan.

3. A coolant system for an oil cooler and an engine comprising a tank for containing a supply of coolant, a pump hydraulically connected to said tank for withdrawing coolant from said tank and circulating it through the oil cooler and the engine, a radiator, a first conduit connecting said pump and the cooler so that at least a portion of the coolant discharged by said pump flows through the oil cooler, a second conduit connecting the cooler and said radiator so that coolant discharged by said pump and flowing through the oil cooler flows also through said radiator, a third conduit connecting said radiator to the engine whereby at least a portion of the coolant passing through said radiator flows also through the engine, a fourth conduit connecting the engine to said tank, substantially all of the coolant discharged by said pump being returned to said tank for recirculation through the system, a fan for

circulating air through said radiator to cool the coolant passing therethrough, means responsive to the temperature of oil leaving the cooler for starting the operation of said fan, and means responsive to the temperature of the coolant in said tank for starting the operation of said fan.

4. A coolant system for an oil cooler and an engine comprising, a tank for containing a supply of coolant, a pump operatively connected to said tank and said cooler for withdrawing coolant from said tank and circulating it through the oil cooler and the engine, a radiator, a conduit connecting the cooler and said radiator for conducting coolant flowing through the cooler into said radiator, a second conduit arranged to receive coolant discharged from said radiator, a third conduit connected to said second conduit and providing for restricted flow of coolant from said second conduit back to said coolant tank, a fourth conduit connecting said second conduit to the engine whereby the portion of coolant in said second conduit which is not returned by said third conduit to said coolant tank flows into the engine, a fifth conduit for conducting the discharge of coolant from the engine back to said tank, a fan for circulating air through said radiator to cool the coolant flowing therethrough, means responsive to the temperature of oil leaving the cooler for starting the operation of said fan, and means responsive to the temperature of the coolant in said tank for starting the operation of said fan.

5. A coolant system for an oil cooler and an engine comprising, a tank for containing a supply of coolant, a pump connected between said tank and said oil cooler for withdrawing coolant from said tank and circulating it through the oil cooler and the engine, a pair of radiators, a conduit connecting the cooler and said radiators for conducting the coolant flowing through the cooler into said radiators, a second conduit arranged to receive the coolant discharged from said radiators, a third conduit connected to said second conduit and providing for restricted flow of coolant from said second conduit back to said coolant tank, a fourth conduit connecting said second conduit to the engine whereby the portion of coolant in said second conduit which is not returned by said third conduit to said coolant tank flows into the engine, a fifth conduit for conducting the discharge of coolant from the engine back to said tank, a pair of fans for circulating air respectively through said radiators to cool the coolant flowing therethrough, means responsive to the temperature of oil leaving the cooler for starting the operation of a first of said fans at a predetermined temperature, means responsive to the temperature of the oil leaving the cooler for starting the operation of the second of said fans at a higher temperature than said predetermined temperature, and means responsive to the temperature of the coolant in said tank for starting the operation of both said fans at a third temperature higher than both of the previously mentioned temperatures.

6. A coolant system for a machine that is normally not running comprising a source of coolant, connections connected to said coolant source including an inlet conduit connected to a coolant inlet of the machine and parallel outlet conduits connected to a coolant outlet of the machine, a normally open valve in the first of said outlet conduits whereby coolant from said coolant source normally circulates through the machine to said coolant source, a thermally operated valve responsive to the temperature of coolant leaving the machine closing the second of said outlet conduits when the temperature of the coolant is below a predetermined minimum, a by-pass connection for diverting coolant from said machine coolant outlet back to said machine coolant inlet, a check valve in said by-pass connection permitting flow of coolant therethrough only from said machine coolant outlet toward the said machine coolant inlet, and an internal pump in the machine for circulating coolant therethrough whereby when the machine starts operation and said normally open valve is closed said internal pump circulates

coolant through said by-pass until the temperature of the coolant leaving the machine reaches said predetermined temperature whereupon said thermally operated valve opens to allow the resumption of circulation of coolant to and from said coolant source.

7. A coolant system for a normally idle engine having a coolant inlet and a coolant outlet chamber, comprising a source of coolant, connections connected to said coolant source including an inlet conduit and parallel outlet conduits, said inlet conduit being connected to the coolant inlet of the engine and said parallel outlet conduits being connected to the coolant outlet chamber of the engine, a pump connected to said coolant source for supplying coolant under pressure to the said inlet conduit, a normally open valve in the first of the said outlet conduits whereby coolant from said coolant source normally circulates through the engine to said coolant source, a thermally operated valve in the outlet chamber responsive to the temperature of coolant leaving the engine normally closing the second of said outlet conduits, a by-pass conduit connected from between the coolant outlet chamber and the normally open valve in said first outlet conduit to said inlet conduit, a check valve in the said by-pass conduit permitting flow of coolant therethrough only from the said first outlet conduit toward the said inlet conduit, and an internal pump in the said engine and driven thereby for circulating coolant therethrough, whereby when the said engine starts operation and the said normally open valve is closed disconnecting said second conduit from said coolant source said internal pump circulates coolant through the said by-pass conduit until the temperature of the coolant leaving the engine reaches a predetermined temperature whereupon the said thermally operated valve opens to allow a resumption of circulation of coolant to and from said coolant source.

8. A coolant system for an oil cooler and a normally idle engine having a coolant inlet and a coolant outlet chamber comprising, a tank for containing a supply of coolant, a pump connected between said tank and the oil cooler for withdrawing coolant from said tank and circulating it through the oil cooler and the engine, a pair of radiators, a first conduit connecting the oil cooler and said radiators for conducting the coolant flowing through the oil cooler into said radiators, a second conduit arranged to receive the coolant discharged from said radiators, a third conduit connected to said second conduit and providing for restricted flow of coolant from said second conduit back to said tank, a fourth conduit connecting said second conduit to the coolant inlet of the engine whereby the portion of the coolant in said second conduit which is not returned by said third conduit to said tank flows into the engine, a pair of parallel outlet conduits connected to the coolant outlet chamber of the engine and arranged to conduct coolant discharged from the engine back to said tank, a normally open valve in the first of said parallel outlet conduits whereby coolant normally circulates through the engine and back to said tank, a thermally operated valve in the outlet chamber responsive to the temperature of coolant leaving the engine normally closing the second of said parallel outlet conduits, a by-pass conduit connected from between the coolant outlet chamber and said normally open valve in said first parallel outlet conduit to said fourth conduit, a check valve in said by-pass conduit permitting flow of coolant therethrough only from said first parallel outlet conduit toward said fourth conduit, an internal pump in the engine and driven thereby for circulating coolant whereby when the engine starts operation and said normally open valve is closed disconnecting said first parallel outlet conduit from said tank, said internal pump circulates coolant through said by-pass conduit until the temperature of the coolant leaving the engine reaches a predetermined temperature whereupon said thermally operated valve opens to allow a resumption of circulation of coolant to and from said tank, a pair of fans for circulating air respectively

through the said radiators to cool the coolant flowing therethrough, means responsive to the temperature of oil leaving the cooler for starting the operation of a first one of said fans at a selected temperature, means responsive to the temperature of the oil leaving the cooler for starting the operation of the second of said fans at a higher temperature than the said selected temperature, and the means responsive to the temperature of the coolant in said tank for starting the operation of both of said fans simultaneously at a third temperature higher than both of the two immediately preceding temperatures.

9. A coolant system for a machine that is normally not running comprising a source of coolant, connections connected to said coolant source including an inlet conduit connected to a coolant inlet of the machine and parallel outlet conduits connected to a coolant outlet of the machine, a normally open valve in the first of said outlet conduits whereby coolant from said coolant source normally circulates through the machine to said coolant source, a first thermally operated valve responsive to the temperature of coolant leaving the machine closing the second of said outlet conduits when the temperature of the coolant is below a predetermined minimum, a by-pass connection for diverting coolant from said machine coolant outlet back to said machine coolant inlet, a check valve in said by-pass connection permitting flow of coolant therethrough only from said machine coolant outlet toward the said machine coolant inlet, a second thermally operated valve adapted to close said first outlet conduit and prevent flow through said by-pass connection when the temperature is above said predetermined minimum, and an internal pump in the machine for circulating coolant therethrough whereby when the machine starts operation and said normally open valve is closed said internal pump circulates coolant through said by-pass until the temperature of the coolant leaving the machine exceeds said predetermined temperature whereupon said first thermally operated valve opens to allow the resumption of circulation of coolant to and from said coolant source, and said second operated valve opens to prevent circulation of coolant through said by-pass connection.

10. A coolant system for an oil cooler and a normally idle engine having a coolant inlet and a coolant outlet chamber comprising, a tank for containing a supply of coolant, a pump connected between said tank and the oil cooler for withdrawing coolant from said tank and circulating it through the oil cooler and the engine, a pair of radiators, a first conduit connecting the oil cooler and said radiators for conducting the coolant flowing through the oil cooler into said radiators, a second conduit arranged to receive the coolant discharged from said radiators, a third conduit connected to said second conduit and providing for restricted flow of coolant from said

second conduit back to said tank, a fourth conduit connecting said second conduit to the coolant inlet of the engine whereby the portion of the coolant in said second conduit which is not returned by the said third conduit to said tank flows into the engine, a pair of parallel outlet conduits connected to the coolant outlet chamber of the engine and arranged to conduct coolant discharged from the engine back to said tank, a normally open valve in the first of said parallel outlet conduits whereby coolant normally circulates through the engine and back to said tank, a first thermally operated valve in the outlet chamber responsive to the temperature of coolant leaving the engine normally closing the second of said parallel outlet conduits, a second thermally operated valve in the outlet chamber adapted to close said first parallel outlet conduit, a by-pass conduit connected from between the coolant outlet chamber and said normally open valve in said first parallel outlet conduit to said fourth conduit, a check valve in said by-pass conduit permitting flow of coolant therethrough only from said first parallel outlet conduit toward said fourth conduit, an internal pump in the engine and driven thereby for circulating coolant whereby when the engine starts operation and said normally open valve is closed disconnecting said first parallel conduit from said tank, said internal pump circulates coolant through said by-pass conduit until the temperature of the coolant leaving the engine reaches a predetermined temperature whereupon said first thermally operated valve opens to allow a resumption of circulation of coolant to and from said tank, said second thermally operated valve closing said first parallel outlet conduit to prevent coolant flow in said by-pass conduit when the temperature of the coolant leaving the engine reaches a predetermined temperature greater than said first mentioned predetermined temperature whereupon all of said coolant circulating through the engine flows to and from said tank, a pair of fans for circulating air respectively through the said radiators to cool the coolant flowing therethrough, means responsive to the temperature of oil leaving the cooler for starting the operation of a first one of said fans at a selected temperature, means responsive to the temperature of the oil leaving the cooler for starting the operation of the second of said fans at a higher temperature than the said selected temperature, and the means responsive to the temperature of the coolant in said tank for starting the operation of both of said fans simultaneously at a third temperature higher than both of the two immediately preceding temperatures.
